UNITED STATES PATENT OFFICE.

ALFRED Z. BAKER, OF NEW YORK, N. Y., ASSIGNOR TO T. B. TOY COMPANY, OF NEWARK,
NEW JERSEY.

WHEELED RECIPROCATING TOY.

1,265,586.

Specification of Letters Patent.

Patented May 7, 1918.

Application filed November 28, 1917. Serial No. 204,383.

To all whom it may concern:

Be it known that I, ALFRED Z. BAKER, a citizen of the United States, and a resident of the city of New York, borough of Manhattan, in the county and State of New York, have invented a new and Improved Wheeled Reciprocating Toy, of which the following is a full, clear, and exact description.

10 My invention relates to a wheeled toy having identical stationary and reciprocating members with means thereon for simulating motion from either side of the stationary or the movable member when the reciprocating member is actuated by the motion of the wheels.

An object of the invention is to provide a simple, inexpensive and attractive toy.

I attain the above and other objects of my invention by the structure conventionally disclosed in the accompanying drawings, wherein similar characters of reference indicate corresponding parts in all the views.

25 Figure 1 is an elevation of a toy embodying my invention, showing the reciprocating member in its raised position;

Fig. 2, a similar elevation showing the reciprocating member in its lowermost position;

Fig. 3, an elevation of the other side from that shown in Fig. 1;

Fig. 4, a vertical section on line 4—4, Fig. 1; and

35 Fig. 5, a side elevation of the toy as it appears in operation.

Referring to the drawings, 6 is a carrier, preferably in the shape of a rectangular board, which is shown with the representation of an animal on its outer face. There are two openings 7 and 8 in said carrier which may represent various parts of the animal's body, depending on the character of the animal. As shown, the opening 7 represents one of the eyes of the animal and the opening 8 represents the mouth. Side members 9 are secured to the longitudinal edges of the carrier 6. These side members extend beyond one end and beyond the rear

50 face of the carrier so as to provide a guide-way for a member 10 which is free to slide between the side members on the carrier. The member 10 is prevented from moving to

and from the carrier by staples 13 anchored in the side members 9. The member 10 carries on its outer surface the representation of an animal, either similar to that shown as illustrated or a different one, if so desired. It has also a pair of openings 11 and 12 adapted to represent some part of the animal's body; in this particular case representing an eye and mouth respectively.

A crank shaft or axle 14 is revolvably mounted in the end of the braces 9. To the projecting end of said axle, wheels 15 are secured. The carrier 6 has a socket 16 for receiving a stick 17 to facilitate the propelling of the toy. A ring or loop 18 is provided on the crank. This loop engages the hooked end 19 of a rod 20 extending from the member 10. The hooked end allows the ring or loop to move along the straight portion of the hooked end and thereby move the member 10 up and down during the rotation of the wheels.

The rear surfaces of both the carrier and member 10 are provided with means to co-operate with the openings in said carrier and member, as, for example, the pupil of an eye is drawn on each inner surface of the carrier and member 10 to co-operate with the eye openings 7 and 11 respectively. Each inner surface of the carrier and the member 10 is also provided with a flexible member 21 which extends through the mouth opening 85 of the member and carrier respectively and which is intended to represent a tongue. The reciprocation of the member 10 during the rotation of the wheels simulates the movement of an eye and tongue of the animal represented on the outer faces of the carrier and member 10, no matter from which side the toy is viewed.

It is self-evident that a rigid member may be secured in place of the flexible member 21 in cases where the representation of the animal is different; also in place of representing the pupil of an eye on the rear faces of the carrier and the movable member 10, a rigid member may be secured to be actuated by the relative movement of the carrier and the movable member.

While I have described the principle of operation, together with the device which I now consider to be the best embodiment thereof, I desire to have it understood that

the device shown is merely illustrative and that such changes may be made as are within the scope of the appended claims.

I claim:

- 5 1. In a toy of the class described, a carrier, wheels for said carrier, an axle for said wheels having a crank, a member mounted to slide on the carrier, means connecting the 70 slideable member to the crank, said carrier and member having openings, and means secured to the inner surface of the carrier and member and projecting through the openings of the member and carrier respectively and adapted to be actuated by the sliding movement of the member when the carrier is moved on its wheels.
- 10 2. In a toy of the class described, a carrier, wheels for said carrier, an axle for said wheels having a crank, a member mounted to 75 slide on the carrier, means connecting the sliding member to the crank, said carrier and member having predetermined representations on their outer surfaces, and means carried by said carrier and member 80 and projecting through the member and carrier respectively and adapted to be actuated by the movement of the sliding member on the carrier.
- 15 3. In a toy of the class described, a carrier having wheels, a member slidably mounted on the carrier and operable by the movement of the wheels, said carrier and member each having an opening, and means associated with the inner faces of 85 the carrier and slideable member and co-operating with the opening in the member and carrier respectively during the movement of the sliding member on the carrier.
- 20 4. In a toy of the class described, a carrier, wheels for the same, a member 90 slideable along the carrier, means interposed between said member and wheels for reciprocating the same on the carrier, said carrier and member having predetermined representations on their outer faces, said carrier and member having openings forming 95 part of the representation, and means secured to the inner faces of the carrier and member and projecting through the opening of the member and carrier respectively, said last mentioned means becoming operative by the sliding movement of the slide- 100 ing member on the carrier.
- 25 5. In a wheeled toy of the class described, two proximate relatively sliding members each having a predetermined representation on its outer face, each of said members having openings, and means secured to each member projecting through the openings of the other becoming operative by the relative movement of said members.
- 30 6. In a wheeled toy of the class described, a pair of proximate relatively movable members, each of said members having an 105

opening, and a flexible member secured to the inner face of each member and projecting through the opening of the other.

7. In a toy of the class described, a member having wheels, a second member slideable along the first member and operable by the movement of the wheels, each of said members having an opening, and a flexible member secured to the inner face of each member so that the flexible member on one 75 projects through the opening of the other.

8. In a toy of the class described, a substantially rectangular member, braces on the longitudinal edges of said member projecting below one end and beyond one face 80 of said rectangular member, a second rectangular member mounted to slide on the face of said first mentioned member between said braces, an axle having a crank revolvably mounted in the ends of the braces 85 projecting beyond the end of the first mentioned member, wheels for actuating said axle, a loop on the crank of the axle, and a rod extending from the movable member and presenting a hook having a straight 90 portion engaging said loop.

9. In a toy of the class described, a member having wheels, a second member mounted to slide along the first by the movement of the said wheels, each of said 95 members having the representation of an animal on the outer face and a pair of openings, one representing an eye and the other the mouth of an animal, a flexible member secured to the inner surface of the 100 movable member and projecting through the mouth opening of the wheeled member, and a flexible member secured to the inner surface of the wheeled member and projecting through the mouth opening of the 105 movable member, the wheeled and movable members having the representation of an eye co-operating with the eye opening of the other member.

10. In a toy of the class described, a 110 substantially rectangular member having the representation of an animal on the outer face and a pair of openings through the body, one representing an eye and the other the mouth of an animal, braces on the longitudinal edges of said member extending below one end and beyond the rear face of said rectangular member, a second rectangular member mounted to slide on the rear face of said first mentioned member between said braces and having the representation of an animal on the other face similar to the animal represented on the first mentioned member, said second member having also a pair of openings, one 115 representing an eye and the other the mouth of an animal, an axle having a crank revolvably mounted in the ends of the braces, wheels for actuating said axle, a loop on the crank of the axle, a rod extending from 120 the crank of the axle, a rod extending from 125 the crank of the axle, a rod extending from 130

the second member and presenting a hook having a straight portion in engagement with said loop, said first member having means for receiving a stick for facilitating the operation of the toy, and a flexible member secured to the inner surface of the first and second mentioned members, the flexible member secured to the first mentioned member projecting through the opening of the second member, and the flexible member secured to the second member projecting through the mouth opening of the first mentioned member, the first and second mentioned members each having the representation of an eye on the inner face thereof co-operating with the eye opening of the other member.

ALFRED Z. BAKER.
